PROCESS FOR THE CRACKING TREATMENT
OF HYDROCARBONS

Arthur D. Smith, Park Ridge, Ill.

Application July 2, 1934, Serial No. 733,479

13 Claims. (Cl. 196—55)

The invention relates to improvements in process and apparatus for the cracking treatment of hydrocarbons and particularly to a process for the continuous production of gasoline of superior quality from heavier petroleum hydrocarbons wherein a portion of an intermediately derived stock, so treated as to be tolerant of the cracking conditions imposed, is returned to such cracking cycle.

10 A process for the production of gasoline has been proposed wherein a composite stock comprising a virgin fraction, and an intermediately derived residual fraction partially clarified through sedimentation, is subjected to cyclic cracking conditions; but such process has never been extensively developed due to deposition of carbon in the cracking coil.

15 The carbon difficulty has been partly solved by effecting an intermediate separation of the cracking stock into distillate and residual fractions, with resubjection of the distillate fraction only to cracking conditions; but such method has fallen somewhat short of the desired optimum through unnecessary fuel expenditure and lower 20 octane value of the gasoline produced than would have obtained under inclusion of a material quantity of a residual fraction in the cracking body.

25 The present process retains the advantages of distillate cracking and improves the quality of the gasoline produced by segregating the products of a cracking reaction into a vaporized fraction and an intermediate residual fraction, followed by resubjecting to such cracking reaction the heavier portions of the vaporized fraction admixed with a material portion of the intermediate residual fraction so treated as to be tolerant of the cracking conditions imposed.

30 To obtain the above objectives the cracking operation is continuously conducted in any conventional type of cracking coil releasing to a vapor separator. The cracking stream, carrying in suspension a finely divided mineral adsorbent of selective adsorptive power towards carbon and/or carbon forming substance, is substantially 35 inhibited from the further production of carbon by suitably reducing its temperature immediately pre or postjacent its point of release to the vapor separator, through direct contact and admixture with a continuously supplied, adsorbent laden 40 and cooler stream of the raw stock to be converted; the cooling effect thereof being supplemented by a suitably interposed, indirect cooling means such as a heat exchanger, preferably serving to preheat the stock charged to the cracking coil. To the raw stock, prior to its contact with

the cracking stream, is continuously admixed a special finely divided mineral adsorbent, relatively large in quantity to the amount carried by the cracking stream, and which while possessing the same general adsorptive characteristic of the former is of heavier specific gravity. Such special adsorbent offers a fresh and highly active surface to the reacting streams as the one is reduced and the other elevated to approximately an incipient cracking temperature, thus supplementing the adsorptive effect of the more or less spent adsorbent derived from the cracking stream at the critical point of tendency towards separation of elementary carbon. In actual practice introduction of the adsorbent carrying raw stock 15 to the cracking stream is effected through contiguous manifold connections, which—including the indirect cooling means—are so closely pre or postjacent the cracking coil release valve, that cooling, inhibition of cracking, introduction of 20 special adsorbent, release and discharge of the admixed adsorbent laden stream to the vapor separator are all practically concurrent and correlated operations.

25 The cooled and released stream immediately enters the primary vapor separator which is preferably constructed in vertical, cylindrical form and provided with a vertical baffle dividing the separator into two sections, each open at either end for the flow of vapor and liquid respectively. 30 A sufficiently reduced pressure is maintained within the separator to admit of the separation and vaporization of the desired light fractions; the latter being conducted to a bubble tower of standard design.

35 The special adsorbent, intimately dispersed in the vaporous mist following release of the admixed stream immediately begins to gravitate to the bottom of the separator; the descending particles forming an adsorptive and cleansing 40 rain of nuclei for the separating globules and droplets of liquid, at the same time dragging down with them the particles of lighter more or less spent adsorbent and associated carbonaceous impurities derived from the cracking stream.

45 The adsorptive action most efficient with initial contact, is also highly effective during the descent of the adsorbent through the intermediate foam layer preceding liquid unity; the separator being 50 maintained at such temperature within the proscribed limits of vaporization and pressure that mild polymerization continuously progresses with the concurrent adsorption of the complexes produced by the adsorbent employed, care being taken through a suitably controlled time factor 55

to preclude any post reactions advancing to the state of free carbon formation.

The spent adsorbent with its associated impurities and a minimum amount of carrying oil is continuously withdrawn from the base of the vapor separator, the supernatant layer of the intermediate residual fraction on the discharge side of the vertical baffle obtaining as a de-polymerized or tolerant stock capable of forming a material fraction of the stock supplied to the cracking coil. Such tolerant stock is conveniently withdrawn from the separator at selective levels precluding any substantial percentage of spent adsorbent being returned to the cracking system; the withdrawn oil being continuously conducted to the base of the bubble tower to unite with the heavier distillate fractions separated therein. The composite stock thus formed, admixed with its appropriate adsorbent, is continuously returned to the cracking cycle and the process repeated as before described.

While the raw stock may be introduced solely as a cooling oil in the manner previously described, and the tolerant stock be so reduced that a portion thereof may be diverted as specification fuel oil, I prefer to concurrently subject a portion of the raw stock, admixed with a portion of the tolerant residual fraction reduced short of fuel specification and withdrawn from the primary vapor separator at a somewhat lower level than the fraction conducted to the bubble tower, to material preheating; employing with such admixture an adsorbent of selective associative action towards natural asphaltenes as well as pyrogenically formed complexes, thus securing progressive pre-adsorption of potential carbon forming bodies without active cracking temperatures being developed.

Under such preferred method of operation, the preheating of the admixed raw stock and tolerant fraction may be conveniently carried out in a pipe still, preferably consisting of a heating coil disposed in the same furnace as the cracking coil; the admixed stock being heated to approximately an incipient cracking temperature and released to a secondary vapor separator. The withdrawn spent adsorbent from the primary vapor separator is continuously pumped to such released stream; it being noted that substantially the entire amount of adsorbent introduced at various points of the system thus passes to the secondary vapor separator as spent material.

The temperature of the released stream, as influenced by the somewhat cooler stream of spent adsorbent and its carrying oil derived from the primary vapor separator, is so correlated to the reduced pressure maintained in the secondary vapor separator that the residual fraction separating therein is of commercial fuel specification after removal of adsorbent by sedimentation; the vaporous fractions passing to the bubble tower and forming a considerable portion of the distillate complement of the composite stock returned to the cracking coil.

The gasoline fractions are recovered from the bubble tower according to standard practice and provision may also be made at this point for withdrawing other light fractions from the system not desired to be returned to the cracking coil.

The fuel oil carrying the final spent adsorbent is continuously withdrawn from the base of the secondary vapor separator under a time factor preventive of undesirable after reactions, cooled, and subjected to sedimentation in any conventional type of settler, preferably a horizontal baf-

fled means from which adsorbent may be intermittently, or continuously withdrawn under automatic control; the clarified fuel being conducted to storage for final settling of traces of adsorbent.

Referring to the character of the adsorbents employed it may be stated at this point that the use of a finely divided mineral adsorbent of characteristic adsorptive action towards carbon and/or carbon forming substance, while dispersed in a cracking body or cracking stream of oil, is the subject of a pending U. S. application, Serial No. 723,144, filed June 30, 1924; the present invention being an improvement over the therein described methods of employing adsorbent, in the particular choice of adsorbent for a specific purpose, and generally in the novel result obtained; i. e., the production of an intermediate residual fraction tolerant to cracking conditions commonly employed in the art.

As a mineral adsorbent possessing selective associative power towards carbon and/or carbon forming substance, may be mentioned lime, fuller's earth, alkaline earth oxides, alumina, kaolinite, bentonite, coke, coal, inert earths, clays of various types, heavy spar, magnesite, bauxite, kieselguhr, silica-gel and the various oxides of iron, but I prefer to employ lime in the form of lime hydrate in the cracking coil, a mixture of such hydrate and fuller's earth flour, with the lime predominating, during preheating; and as the special adsorbent, lime hydrate (colloidal or non-colloidal) and/or fuller's earth flour. The selection is based partly on account of the ready accessibility and cheapness of the adsorbents recommended, but principally on account of their high adsorptive and associative power towards resinous carbon forming substance and from the fact that they may be procured in varying specific gravities and/or physical structure.

Further, lime hydrate loses approximately 75% of its water of constitution somewhat below the cracking temperatures commonly employed in the art; the theory being offered that release of such water forms ultra microscopic fissures and pores in the lime particles highly beneficial in the treatment involved. Possibly a certain amount of absorption of still soluble petrolenes and carbenes occurs in conjunction with the pre-adsorption of asphaltenes or other highly complex hydrocarbon polymerides.

The employment of non-colloidal lime hydrate in a cracking cycle to achieve a ready separation of such adsorbent and its associated carbon products from a final residuum has been proposed in U. S. Patent No. 1,913,619, but where the rate of settling is below a commercial optimum, such patent mentions filtration as a method of separation. The present invention maintains a commercial optimum in the rate of settling, thus avoiding any necessity of filtration, through admixture of sufficient fuller's earth flour with the lime hydrate (preferably in non-colloidal form) as to insure a specific gravity dominating internal friction; the ratio of fuller's earth being increased to the complete exclusion of the lime hydrate if the nature of the residual fraction so requires. Fuller's earth can be more readily obtained in varying densities and degrees of fineness, thus enabling a grade to be selected best suited for the particular conditions involved.

The quantity of adsorbent employed will depend on its chemical composition, degree of fineness, density and physical structure, the extent

of cracking, preheating and post-polymerization practiced, as well as the nature of the raw stock. In general from one-quarter to one pound of adsorbent per barrel of oil treated will be ample for the oil charged to the cracking coil, approximately the same quantity during preheating, and from one-half to two pounds for the special adsorbent; a total of two and one-half pounds for the three concurrent operations being usually sufficient in commercial practice. In each instance the adsorbents are preferably initially incorporated in separate mixing tanks with relatively small quantities of the respective oils undergoing treatment; the slurries thus produced being continuously fed in predetermined amounts to the respective means involved by methods well known in the arts.

Apart from the hypotheses advanced, explanations given and quantities of adsorbent mentioned, the significant fact remains that where there concurrently exists adsorption of carbon and/or carbon forming substance in the cracking coil, pre-adsorption of potential carbon forming substance during pre-heating and post-adsorption of carbonaceous products formed under incipient cracking conditions, a more than merely additive result is obtained as evidenced by the improvement in the quality of gasoline produced, the relatively small total quantity of adsorbent required, and the highly important production of an intermediate residual fraction which, when freed from spent adsorbent and its associated impurities, may be continuously returned in a material quantity to the cracking cycle. The importance of being able to resubject to such cycle a product having a preponderance of double bond hydrocarbon compounds, such as usually obtains in the tolerant residual fraction, cannot be over estimated in the production of gasoline of high anti-knock value.

Further while the degree of tolerancy of the clarified residual fraction to cracking conditions is obviously limited by the extent of the cracking obtained per pass, the temperature and pressure carried in the cracking coil, as well as by the nature of the raw stock itself, the improvements in process herein described admit of introduction to the cracking coil of a composite stock containing from 10% by volume of clarified residual stock under severe liquid vapor phase cracking treatment up to 45% and over under favorable conditions; 30% being a fair average and the minimum 10% a decidedly material quantity. Further the saving in heat due to minimizing the thermal units absorbed in unnecessary vaporization incident to maximum distillate separation is considerable. Other advantages will occur to one skilled in the art.

In order that the invention may be better understood, reference is made to the attached drawing where Fig. 1 represents in diagrammatic form an apparatus suitable for carrying out the process; and wherein a high pressure charging pump 1, supplied through the line 2 with composite stock from the bubble tower 3, delivers such charging stock via lines 4 and 5 through the preferably parallel flow type of heat exchanger 6 to the cracking coil 7 disposed in the furnace 8. The pump 9, supplied with adsorbent (lime) slurry from the mixing tank 10, delivers such slurry at a predetermined rate through an extension of the line 4, as controlled by valve 11, to admix with the charging stock as it enters the line 5; thus insuring a proper amount of adsorbent be-

ing carried in suspension during the cracking phase.

The converted stock from the cracking coil 7 is released via the transfer line 12, through the heat exchanger 6 and lines 13 and 14 as controlled by the cracking coil release valve 15, to the primary vapor separator 16. The pump 17, supplied through the line 18 with the cool raw stock to be converted from the tank 19, as controlled by valve 20, delivers such stock via lines 21, 22 and 13, as controlled by valve 23, to admix with the cracking stock and effect a reduction in temperature thereof inhibitive of further carbon formation substantially at the point where the latter is released from the heat exchanger and the pressure of the cracking coil. The pump 24, supplied with adsorbent (lime and fuller's earth, or fuller's earth) slurry from the mixing tank 25, (fed with oil from the tank 19, as controlled by valve 26) delivers such slurry at a predetermined rate through the line 22 as controlled by valve 27, to enter the line 13; thus insuring a proper amount of adsorbent being carried in suspension by the cooling oil as it contacts the cracking stream, and a sufficient excess to act as a de-polymerizer in the vapor separator. If desired a portion of the raw stock employed as a cooling oil may be moderately preheated by diverting a part of the flow of line 21 to line 28, as controlled by valve 29, through the heat exchanger 30, and thence by line 31 to the line 13.

The primary vapor separator 16, into which the cooled and adsorbent laden stream from the cracking coil is released, is provided with a median, vertical baffle 32, dividing a substantial portion of such separator into two open end sections 33 and 33' respectively. The vapor line 34 conducts the separated vaporous fractions to the bubble tower 3 while the withdrawal line 35, as controlled by valve 36 (preferably of automatically operated type) provides for the removal of the spent adsorbent and its associated impurities as it subsides to the bottom of the separator. Disposed on the vertical shell of the section 33' at suitable levels insuring adequate settlement, are the selective withdrawal lines 37, 38 and 39 as controlled by their respective valves 37', 38' and 39' for release of the supernatant, tolerant residual stock; such lines connecting to the flow line 40 which conducts the de-polymerized or tolerant stock through the down-comer 3' to the base of the bubble tower 3, from whence, admixed with the heavier distillate fractions condensed therein, composite charging stock is returned to the system as previously described.

In the preferred method of operation a portion of the raw stock delivered by the pump 17 and moderately preheated in its passage through the heat exchanger 30, is fed through the line 41 to the discharge side of the pump 42; the valve 43 and 44 affording control of the fractions delivered to lines 13 and 41 respectively. Adsorbent slurry is supplied to the fraction of the raw stock fed through line 41 by pump 24 via lines 22 and 45, as controlled by valve 45'; the valve nest 27 and 45' admitting of selective quantities of adsorbent (lime and fuller's earth, or fuller's earth) being supplied to the respective raw stock fractions, as will be apparent to one skilled in the art. The moderately heated and adsorbent laden stream fed through the line 41 is admixed at the discharge side of pump 42 with a stream of tolerant stock withdrawn by such pump through line 46 from section 33' of the vapor separator. The united stream of raw and toler-

ant stocks as delivered through line 47 may receive a further increment of adsorbent (lime) supplied by pump 8 through lines 4 and 48, as controlled by valve 49. The final admixed stream then passes to the preheating coil 50 disposed in the cooler portion of the furnace 8, from which coil the admixed stock, raised to an incipient cracking temperature, is discharged through the line 51, as controlled by the pressure release valve 52, to enter the secondary vapor separator 53; the discharged oil receiving in its passage to such separator the spent adsorbent withdrawn from the base of the primary separator through the line 35 with introduction thereof to the line 51 being effected by pump 54 and line 54'.

Specification fuel oil and spent adsorbent is continuously withdrawn from the settling well 53' of the secondary vapor separator 53, through line 55 as controlled by valve 55' (preferably of automatic type), and thence through cooler 56 and line 56' to enter the horizontal settler 57. From the latter, spent adsorbent is withdrawn by lines 58 and 58', as controlled by valves 59, 60 and 61, through cooler 62 to be discharged from the system as a waste product. The supernatant, clarified, specification fuel flowing over baffle 57' is continuously withdrawn from the system through line 63, as controlled by valve 64, and pumped by pump 65 through cooler 66 to storage.

Vapors generated in the settler 57 escape through the line 67 to the bubble tower 3. The vapor line 68 conducts vaporous fractions released in the secondary vapor separator 53 through the outer jacket of the exchanger 30 to enter the line 34, and thus pass to the bubble tower 3 along with vaporous fractions from the primary vapor separator 16.

The bubble tower 3 which is of standard construction may be provided with an intermediate stripping device (not shown) for removal of relatively heavy light fractions, such as for instance kerosene distillate; the light gasoline fractions escaping through vapor line 69 to be condensed by condenser 10. The liquefied gasoline flows through line 71 to receiving drum 12, from whence a fraction of the condensate may be returned through line 73, pump 74 and line 75 terminating in the perforated coil 76 to serve as trim stock. Uncondensed gas escapes through line 77, as controlled by valve 78, (preferably of automatic relief type); while the preferred gasoline is withdrawn from the system by line 79 as controlled by valve 80.

As an example of operative temperatures and pressures, the converted stock leaving the cracking coil may obtain at 900° F. under 500 lbs. pressure, and the tolerant residual stock may be withdrawn from the primary vapor separator at 675° F. under 75 lbs. pressure, while the secondary vapor separator is maintained at approximately 780° F.; but it is to be clearly understood that such values are to be considered illustrative only of conditions that may prevail; the process generally admitting of the widest divergent temperatures and pressures commonly practiced under liquid-vapor phase cracking. The process is moreover not limited to the particular type or relative size of the apparatus herein shown, nor to the exact quantities of adsorbent mentioned, which are given for purposes of example only. It is to be further understood that the apparatus is equipped with the usual safety valves, indicating and recording pressure and temperature

gauges, liquid level controls, etc., commonly employed in the arts.

What I claim is new and desire to protect by Letters Patent is:

1. A process for converting heavier hydrocarbon oil into lighter hydrocarbon which comprises subjecting said oil commingled with finely divided mineral adsorbent towards carbon forming substance to a cracking temperature under superatmospheric pressure, admixing with said oil simultaneously with reduction in temperature thereof to an incipient cracking stage finely divided mineral adsorbent of the same general characteristics but heavier than said first mentioned adsorbent, substantially concurrently with such reduction in temperature releasing the so treated oil to a zone of reduced pressure, and separating therein respectively as vapor and liquid under accelerated sedimentation by such heavier adsorbent said lighter hydrocarbon and a clarified residual fraction employable as fuel oil without further treatment.

2. A process for converting heavier hydrocarbon oil into lighter hydrocarbon which comprises subjecting said oil commingled with finely divided mineral adsorbent towards carbon forming substance, such as lime, to a cracking temperature under superatmospheric pressure, admixing with said oil simultaneously with reduction in temperature thereof to an incipient cracking stage additional finely divided mineral adsorbent of the same general adsorptive characteristics but heavier than said first mentioned adsorbent, such as fuller's earth, substantially concurrently with such reduction in temperature releasing the so treated oil to a zone of reduced pressure, and separating therein respectively as vapor and liquid under accelerated sedimentation by such heavier adsorbent said lighter hydrocarbon and a clarified residual fraction employable as fuel oil without further treatment.

3. A process for converting heavier hydrocarbon oil into lighter hydrocarbon which comprises subjecting said oil commingled with finely divided lime to a cracking temperature under superatmospheric pressure, admixing with said oil simultaneously with reduction in temperature thereof to an incipient cracking stage finely divided fuller's earth in quantity relatively large to said lime, substantially concurrently with such admixture releasing the so treated oil to a zone of reduced pressure and separating therein respectively as vapor and liquid under accelerated sedimentation by said fuller's earth said lighter hydrocarbon and a clarified residual fraction employable as fuel oil without further treatment.

4. A process for converting heavier hydrocarbon oil into lighter hydrocarbon which comprises subjecting said oil commingled with finely divided lime to a cracking temperature under superatmospheric pressure, admixing with said oil simultaneously with reduction in temperature thereof to an incipient cracking stage finely divided heavy spar in quantity relatively large to said lime, substantially concurrently with such admixture releasing the so treated oil to a zone of reduced pressure and separating therein respectively as vapor and liquid under accelerated sedimentation by said heavy spar said lighter hydrocarbon and a clarified residual fraction employable as fuel oil without further treatment.

5. A process for converting heavier hydrocarbon oil into lighter hydrocarbon which comprises subjecting said oil commingled with finely divided lime to a cracking temperature under superat-

mospheric pressure, admixing with said oil simultaneously with reduction in temperature thereof to an incipient cracking stage finely divided lime with a dominant quantity of heavier adsorbent substantially concurrently with such admixture releasing the so treated oil to a zone of reduced pressure and separating therein respectively as vapor and liquid under accelerated sedimentation by said heavier adsorbent said lighter hydrocarbon and a clarified residual fraction employable as fuel oil without further treatment.

6. A process for converting heavier hydrocarbon oil into lighter hydrocarbon which comprises subjecting said oil commingled with finely divided mineral adsorbent towards carbon forming substance to a cracking temperature under superatmospheric pressure, admixing with said oil substantially simultaneously with reduction from said cracking temperature to an incipient cracking stage finely divided mineral adsorbent of the same general adsorptive characteristics but heavier than said first mentioned adsorbent, substantially concurrently with such reduction in temperature releasing the so treated oil to a zone of reduced pressure, and separating therein respectively as vapor and liquid under accelerated sedimentation by such heavier adsorbent said lighter hydrocarbon and a clarified residual fraction employable as fuel oil without further treatment.

7. A cyclic process for converting heavier hydrocarbon oil into lighter hydrocarbon which comprises subjecting a composite stock derived from said oil and commingled with finely divided mineral adsorbent towards carbon forming substance to a cracking temperature under superatmospheric pressure, admixing with said composite stock such volume of cooler said heavier hydrocarbon oil commingled with finely divided mineral adsorbent of the same general adsorptive characteristics but heavier than said first mentioned adsorbent as to reduce the temperature of said stock to an incipient cracking stage, substantially concurrently with such reduction in temperature releasing the admixed stream to a zone of reduced pressure, separating therein respectively as vapor and liquid under accelerated sedimentation by said heavier adsorbent said lighter hydrocarbon and a clarified residual fraction, and returning said clarified residual fraction as a portion of said composite stock to cracking conditions as aforesaid.

8. A cyclic process for converting heavier hydrocarbon oil into lighter hydrocarbon which comprises subjecting a composite stock derived from said oil and commingled with finely divided mineral adsorbent towards carbon forming substance to a cracking temperature under superatmospheric pressure, admixing with said composite stock such volume of cooler said heavier hydrocarbon oil commingled with finely divided mineral adsorbent of the same general adsorptive characteristics but heavier than said first mentioned adsorbent as to reduce the temperature of said stock to an incipient cracking stage, substantially concurrently with such reduction in temperature releasing the admixed stream to a zone of reduced pressure, separating therein respectively as vapor and liquid under accelerated sedimentation by said heavier adsorbent said lighter hydrocarbon and a clarified residual fraction, dephlegmating said vapor into gasoline and distillate, admixing with said distillate said clarified residual fraction and returning such admix-

ture as said composite stock to cracking conditions as aforesaid.

9. A cyclic process for converting heavier hydrocarbon oil into lighter hydrocarbon which comprises subjecting a composite stock derived from said oil and commingled with finely divided lime to a cracking temperature under superatmospheric pressure, admixing with said composite stock such volume of cooler said heavier hydrocarbon oil commingled with finely divided fuller's earth in a relatively large quantity to said lime as to reduce the temperature of said stock to an incipient cracking stage, substantially concurrently with such reduction in temperature releasing the admixed stream to a zone of reduced pressure, separating therein respectively as vapor and liquid under accelerated sedimentation by said heavier adsorbent said lighter hydrocarbon and a clarified residual fraction, dephlegmating said vapor into gasoline and distillate, admixing with said distillate said clarified residual fraction and returning such admixture as said composite stock to cracking conditions as aforesaid.

10. A cyclic process for converting heavier hydrocarbon oil into lighter hydrocarbon which comprises subjecting a composite stock derived from said oil and commingled with finely divided mineral adsorbent towards carbon forming substance to a cracking temperature under superatmospheric pressure, admixing with said composite stock such volume of cooler said heavier hydrocarbon oil commingled with finely divided mineral adsorbent of the same general adsorptive characteristics but heavier than said first mentioned adsorbent as to reduce the temperature of said stock to an incipient cracking stage, substantially concurrently with such reduction in temperature releasing the admixed stream to a zone of reduced pressure, separating therein respectively as vapor and liquid under accelerated sedimentation by said heavier adsorbent said lighter hydrocarbon and a clarified residual fraction, subjecting a portion of said clarified residual fraction admixed with said heavier hydrocarbon oil commingled with said heavier adsorbent to incipient cracking conditions, releasing such admixture together with spent adsorbent discharged from said zone of reduced pressure to a zone of less pressure than preceding, separating therein respectively as vapor and liquid additional distillate and adsorbent containing residuum, subjecting said residuum to accelerated sedimentation productive of a clarified fuel oil, uniting the vapors of said additional distillate and said lighter hydrocarbon and dephlegmating therefrom gasoline and a residual distillate, admixing with said residual distillate a portion of said clarified residual fraction and returning such admixture as said composite stock to cracking conditions as aforesaid.

11. A cyclic process for converting heavier hydrocarbon oil into lighter hydrocarbon which comprises subjecting a composite stock derived from said oil and commingled with finely divided lime to a cracking temperature under superatmospheric pressure, admixing with said composite stock such volume of cooler said heavier hydrocarbon oil commingled with finely divided fuller's earth in quantity relatively large to said lime as to reduce the temperature of said stock to an incipient cracking stage, substantially concurrently with such reduction in temperature releasing the admixed stream to a zone of reduced pressure, separating therein respectively as vapor and liquid under accelerated sedimentation by

- 5 said heavier adsorbent said lighter hydrocarbon and a clarified residual fraction, subjecting a portion of said clarified residual fraction admixed with said heavier hydrocarbon oil commingled with fuller's earth to incipient cracking conditions, releasing such admixture together with spent adsorbent discharged from said zone of reduced pressure to a zone of less pressure than preceding, separating therein respectively as 10 vapor and liquid additional distillate and adsorbent containing residuum, subjecting said residuum to accelerated sedimentation productive of a clarified fuel oil, uniting the vapors of said additional distillate and said lighter hydrocarbon 15 and dephlegmating therefrom gasoline and a residual distillate, admixing with said residual distillate a portion of said clarified residual fraction and returning such admixture as said composite stock to cracking conditions as aforesaid.
- 20 12. A process for converting heavier hydrocarbon oil into lighter hydrocarbon which comprises subjecting said oil commingled with finely divided mineral adsorbent towards carbon forming substance to a cracking temperature under superatmospheric pressure, admixing with said oil while at said cracking temperature finely divided mineral adsorbent of the same general adsorptive characteristics but heavier than said first mentioned adsorbent, substantially concurrently with 25 such admixture reducing the temperature of said
- oil to an incipient cracking stage and releasing to a zone of reduced pressure, and separating therein respectively as vapor and liquid under accelerated sedimentation by such heavier adsorbent said lighter hydrocarbon and a clarified residual fraction employable as fuel oil without further treatment.
13. A cyclic process for converting heavier hydrocarbon oil into lighter hydrocarbon which comprises subjecting a composite stock derived from said oil and commingled with finely divided mineral adsorbent towards carbon forming substance to a cracking temperature under superatmospheric pressure, admixing with said composite stock obtaining at said cracking temperature cooler said heavier hydrocarbon oil commingled with finely divided mineral adsorbent of the same general adsorptive characteristics but heavier than said first mentioned adsorbent, substantially concurrently with such admixture reducing the temperature of the admixed stream to an incipient cracking range and releasing to a zone of reduced pressure, separating therein respectively as vapor and liquid under accelerated sedimentation by said heavier adsorbent said lighter hydrocarbon and a clarified residual fraction, and returning said clarified residual fraction as a portion of said composite stock to cracking conditions as aforesaid.

ARTHUR D. SMITH. 30
